UNITED STATES PATENT OFFICE.

ABE R. SPIELBERGER, OF ATLANTA, GEORGIA.

FOUNTAIN-COMB.

1,256,386.

Specification of Letters Patent. Patented Feb. 12, 1913.

Application filed August 31, 1917. Serial No. 189,190.

To all whom it may concern:

Be it known that I, ABE R. SPIELBERGER, a citizen of the United States, residing at Atlanta, in the county of Fulton and State of Georgia, have invented new and useful Improvements in Fountain-Combs, of which the following is a specification.

This invention relates to combs, and more particularly to that class thereunder known 10 as fountain combs.

The primary object of the invention resides in the production of a comb of the above stated character, wherein a novel construction of means is employed for feeding 15 the pomade into the hollow comb teeth, to facilitate the application of such directly to the scalp, without the excessive moistening of the hair or the usual manipulation of the fingers.

With the above and other objects in view, 20 the invention consists in the novel features, details of construction and combination of parts which will hereinafter be more fully set forth, illustrated in the accompanying 25 drawings, and pointed out in the appended claims.

Figure 1 is a side elevation of the comb with the handle portion thereof in longitudinal section;

Fig. 2 is a horizontal sectional view;

Figs. 3 and 4 are cross sections on the lines 3—3 and 4—4 respectively of Fig. 2;

Fig. 5 is a perspective detail of the pouch;

Fig. 6 is a perspective detail of the handle 35 with the pouch therein, illustrating a slight modification.

Referring more particularly to the accompanying drawing, in which like characters of reference refer to corresponding parts in 40 the several views, the fountain comb generally comprises a back 5 provided with a longitudinal passage 6 through which the medicaments contained in the compressible tube or pouch 7 are distributed to and 45 through the communicating channels 8 in certain of the teeth 9 which are preferably broad and hollow, by means of a feeder to be hereinafter referred to. The inner end of the back 5 is preferably enlarged into a head 3 and the inner end of the head is in 50 turn reduced into a stud 4, preferably threaded as shown.

The tube or pouch 7 which is of compressible material has at its inner end an enlarged rigid head 7' which is preferably 55 hexagonal as shown, and from this head the

body of the pouch may taper slightly to its outer end, the latter being preferably pointed as shown at 12, and closed. Fixed through the center of the head 7' is a 60 threaded nipple 11 adapted to be screwed onto an axial socket 10 (see Fig. 1) formed in the inner end of the comb head 3 and communicating with the passage 6. Thus when the tube as a whole is turned with respect to the comb as a whole, the parts are 65 screwed together, and their relative rotation in the opposite direction disconnects these parts.

The handle 14 is preferably of cylindrical 70 external contour, rounded and closed at its outer end as at 17, and having an open mouth 15 at its inner end. Its mouth may be threaded as shown so as to screw onto the threads of the stud 4, with a set screw 16 75 employed to hold the handle against displacement. Internally the handle is preferably hexagonal as shown at 20 to conform with the contour of the head 7'. In the sides of the handle is a pair of longitudinally 80 disposed slots 18 arranged diametrically. One of the walls forming each of the slots is provided with a series of teeth 19. The hollow formation of this handle provides within the same a chamber to accommodate 85 the compressible tube 7, and the feeder for compressing or squeezing the tube is designated generally by the character 21.

Said feeder consists of a shaft 22 extending across the interior of the handle and 90 having fixed upon it two small gears 23 which mesh with the teeth 19 in the slots 18, a spherical presser or ball fast on the shaft within the handle and of a size to compress the pouch 7 as best seen in Fig. 1, and a 95 small knob or cross bar 24 secured to one end of the shaft outside the handle 14. By grasping this cross bar and rotating the shaft, the gears travel on the teeth and cause a progressive movement of the entire feeder 100 21, the ball 25 rolling on the tube in a manner which will be clear and compressing it slowly so that its contents will be forced through the nipple 11 and along the passages 6 and 8, to be distributed by the broad 105 comb teeth 9 directly onto the scalp without excessive wetting of the hair or the usual manipulation of the fingers.

A slight amplification is illustrated in Fig. 6, where a sleeve 26 is slidably mounted 110 around the handle 14, and the shaft 22 has trunnions extended at 27 through bearings

in both sides of the sleeve as shown. Thus when this shaft is turned and the feeder progresses, the sleeve slides along the handle and carries with it the bearings for the 5 shaft.

In assembling the parts of this device, the nipple 11 may be screwed into the socket first if the mouth 15 of the handle is simply slipped onto the stud 4 and held by a set 10 screw 16. But if said mouth and stud are threaded as shown, the tube will be first put into the handle and its head 7' pushed back beyond the mouth into the hexagonal 15 interior 20 thereof, and then when the handle is screwed onto the stud the nipple will be simultaneously screwed into socket. A reverse motion separates the parts.

From the foregoing description, taken in connection with the accompanying drawing, 20 the advantages of construction and the method of operation will be readily apparent to those skilled in the art to which the invention relates; and while I have described the principles of operation of the invention, together with the device which I now consider to be the best embodiment thereof, I desire to have it understood that the device shown is merely illustrative, and that such changes may be made when desired as are within the scope of the appended 25 claims.

What is claimed as new is:—

1. A fountain comb comprising a back provided with a passage and teeth having 30 channels communicating with said passage, a handle therefor, a compressible pouch arranged in said handle and having connection at the rear end of the passage, and means rotatably mounted in the handle for 35 pressing the pouch to distribute the contents thereof into said channels, substantially as and for the purpose specified.

2. A device of the class described comprising a comb back provided with a passage communicating with certain of the 40 teeth, a slotted handle connected at one end to said back, a compressible pouch in said handle and communicating with the passage, and means mounted in the slots of the 45 handle for compressing the pouch, substantially as and for the purpose specified.

3. In a device of the character described, a comb back having a passage and a plurality of hollow teeth having communication 50 with said passage, a handle removably connected to the back and provided with a pair of slots, a compressible pouch in said handle, a shaft rotatably journaled in the slots of the handle, a presser on said shaft, 55 and means for rotating the shaft to cause the contact of the presser with said pouch, substantially as and for the purpose specified.

4. In a device of the character described, 60 a comb back having a passage and a plu-

rality of hollow teeth having communication with said passage, a handle connected to the back and provided with a pair of slots, a compressible pouch in said handle, a shaft traversing the handle and journaled 70 in the slots thereof for rotary movement, means on said shaft for progressing the same in the slots of the handle in a direction toward the comb back, and means interposed between the latter mentioned 75 means for causing the compression of the pouch as the shaft is advanced in said handle.

5. In a fountain comb, the combination with the tubular back and teeth, and a tubular handle slotted longitudinally in opposite sides; of a compressible pouch within 80 said handle connected with the bore of the back, a rolling feeder also therein, and a shaft fixed through the feeder and projecting out said slots.

6. In a fountain comb, the combination with the tubular back and teeth, and a tubular handle slotted longitudinally in opposite sides and having teeth along one 90 edge of the slots; of a compressible pouch within said handle connected with the bore of the back, a rolling feeder also therein, a shaft fixed through the feeder and projecting out said slots, and gears fast on the 95 shaft within said slots and engaging said teeth.

7. In a fountain comb, the combination with the tubular back and teeth, and a tubular handle slotted longitudinally in opposite 100 sides and having teeth along one edge of the slots; of a compressible pouch within said handle connected with the bore of the back, a rolling feeder also therein, a shaft fixed through the feeder and projecting out said slots, gears fast on the shaft, a sleeve slidably inclosing the handle and gears and in which the trunnions of the shaft are journaled, and a handle on one end of said shaft.

8. In a device of the character described, the combination with a delivery member having a longitudinal passage with a threaded socket at its inner end, a tubular handle, and means for detachably connecting the inner ends of the handle and member; of a pouch, a rigid head at the inner end thereof adapted to slidably engage the interior of the handle, a threaded outlet nipple on said head adapted to engage said 115 socket, and means within the handle for compressing the pouch.

9. In a device of the character described, the combination with a delivery member having its inner end enlarged into a head 120 and the head reduced into a round stud, this member being provided with a passage terminating in a threaded socket opening axially through said stud, a tubular handle closed at its outer end, and having its inner 125 end.

end shaped to engage said stud, and means for holding it detachably in such engagement; of a pouch, a rigid head at the inner end thereof adapted to slidably engage the interior of the handle, a threaded outlet nipple on said head adapted to engage said socket, and means within the handle for compressing the pouch.

10. In a device of the character described, the combination with a delivery member having a stud at its inner end and provided with a longitudinal passage communicating with a socket opening through the axis of said stud, and a tubular handle internally 15 angular except that its inner end is threaded to engage said stud; of a pouch within the handle, a rigid head at the inner end of the pouch angular in contour to slidably engage the interior of the handle, an outlet 20 nipple opening through the head and adapted to engage said socket, and a traveling

feeder within the handle for compressing the pouch.

11. In a device of the character described, the combination with a delivery member having a stud at its inner end and provided with a longitudinal passage opening through the axis of said stud, a pouch having a rigid head of angular contour with an outlet adapted to align with said passage, and means for connecting the head with the stud by relative rotation; of a tubular handle inclosing the pouch and having a threaded mouth for engagement with said stud, its interior being angular for engagement with said head, and its body being longitudinally slotted, and a traveling feeder within the handle provided with operating means projecting through said slot.

In testimony whereof I affix my signature. 40

ABE R. SPIELBERGER.
